CLAIM

The ornamental design for a display screen or portion thereof with graphical user interface, as shown and described.

DESCRIPTION

FIG. 1 is a front view of a display screen or portion thereof as positioned on an oven; and,

FIG. 2 is a front view of the display region of FIG. 1 enlarged for clarity.

The outermost broken line rectangle in FIG. 2 depicts a display screen or portion thereof. Broken lines in the figures outside that rectangle illustrate environment. The remaining broken lines depict portions of the graphical user interface. All broken lines form no part of the claimed design.
